UNITED STATES PATENT OFFICE.

MAX W. HENIUS AND JOHN HERROLD, OF NEW YORK, N. Y.; SAID HERROLD
ASSIGNOR TO SAID HENIUS.

MACHINE FOR ASSEMBLING CORSET EYES AND RIVETS, &c.

SPECIFICATION forming part of Letters Patent No. 665,092, dated January 1, 1901.

Application filed September 17, 1900. Serial No. 30,223. (No model.)

To all whom it may concern:

Be it known that we, MAX W. HENIUS and JOHN HERROLD, citizens of the United States, and residents of the borough of Brooklyn, in the city and State of New York, have invented a new and useful Improvement in Machines for Assembling Corset Eyes and Rivets and Conveying and Riveting Them, of which the following is a specification.

10 This invention relates to an improvement in machines for assembling eyes and rivets, and after they have been assembled feeding them to a predetermined point.

Our invention further relates to an improvement in machines for assembling eyes and rivets and then feeding them to a predetermined point in such a manner that they may be rapidly and efficiently riveted to the corset-steel.

20 A practical embodiment of our invention is represented in the accompanying drawings, in which—

Figure 1 represents our improved machine in front elevation. Fig. 2 is a top plan view of the same. Fig. 3 is a partial top plan view, certain of the parts being broken away to more clearly show the parts beneath them. Fig. 4 is a side view of the machine, certain portions of the same being broken away to more clearly show the interior construction thereof. Fig. 5 is a partial vertical section taken from front to rear through the base of the machine to show more clearly the means for feeding the eyes into position to receive the rivets and then advance them into the delivery-wheel. Fig. 6 is an enlarged detail vertical section taken from front to rear through a portion of the machine to show more clearly the means for assembling the rivets and eyes.

30 Fig. 6^a is a detail transverse section taken on the line 6^a 6^a of Fig. 6. Fig. 7 is a front view of the same. Fig. 8 is a detail reverse sectional view on the same scale as Figs. 1 to 5, inclusive, showing the manner of controlling the feeding of the rivets to the eyes. Fig. 9 is a detail view, on an enlarged scale, showing the manner of engaging the corset-steel with the eye preparatory to withdrawing the eye from the delivery-wheel. Fig. 10 is an-45 other detail view, on an enlarged scale, showing the eye and corset-steel withdrawn from

the wheel and placed in position upon the anvil ready to have the eye secured permanently to the steel by upsetting the ends of the rivets. Fig. 11 represents a front view 55 of the pair of reciprocating boxes at the lower ends of the chutes, showing more clearly the spring-actuated arms for temporarily retaining the lowermost pair of rivets in the chutes until they are positively withdrawn after they have been engaged by the eye. Fig. 12 is a vertical section through one of the boxes in the plane of the chute therein, and Fig. 13 is an inverted plan view of the said boxes.

The base of the machine is denoted by A, 65 and uprising from the rear thereof are suitable posts a a', in which is rotatably mounted the main drive-shaft B.

The base A is provided at its front with a centrally-arranged post a², which forms a support for the riveting-anvil C. This anvil C is provided with a lateral extension c, serving as a rest for the corset-steel when the eye is being riveted thereto. This lateral extension c is made of harder material than the 70 balance of the anvil, and it may be shifted longitudinally thereon to present a new surface for the hammer of the riveting device to strike when one portion becomes too much worn. This anvil is further provided with a 75 projection c', uprising therefrom, which is arranged to enter the slot in the eye to properly locate the eye and steel with respect to the hammer and anvil while the eye is being riveted to the steel. The base A is further provided at points intermediate its front and rear with a pair of posts or stanchions a³ a⁴, in which is rotatably mounted the delivery-wheel shaft D, to which is imparted an intermittent rotary motion in one direction from 80 the main drive-shaft in a manner to be hereinafter set forth. The base A is further provided at points intermediate the pair of posts a a' and the pair of posts a³ a⁴ with a pair of posts a⁵ a⁶, which form supports for the bed-plate E, onto which are fed the eyes F and rivets G in the manner to be hereinafter described.

A rivet-reservoir-supporting frame H up-95 rises from the base A, and there is mounted to rotate in its top a main rivet-supply reser-100 voir I, the shaft i of which has fixed thereto

a suitable driving-pulley i' , which may be driven at the required speed by a belt. (Not shown herein.) This reservoir may be supplied with rivets through an opening normally closed by the stopper i^2 .

5 The reservoir I is preferably of closed hollow cylindrical form, and it is provided through its periphery with one or more pairs of exit-holes i^3 , through which the rivets are permitted to escape when the pair of holes is at its lowermost point during the rotation of the reservoir.

10 A pair of troughs J J' is hinged on a cross-shaft h , supported by arms $h' h^2$, projecting from the frame H, the upper ends of the said troughs J J' projecting beneath and to the rear of the rivet-reservoir in line with the holes i^3 , the said troughs being further provided with branches $J^2 J^3$, which extend beneath and to the front of the rivet-reservoir in line with the holes i^3 .

15 An overflow-rivet reservoir K is carried by the frame H, into which reservoir project the lower ends of the hinged pair of troughs J J'. 20 The bottoms of the troughs are open for a distance to permit incomplete rivets to fall therethrough into the reservoir K, so as not to impede the alining of the perfectly-formed rivets.

25 30 A pair of rivet-chutes L L' extends downwardly from the overflow-reservoir K, where the chutes are connected with their respective troughs J J' for receiving the rivets as they slide from the said troughs.

35 40 The construction of the lower ends of the troughs J J' is such that as the rivets slide from the upper portions of the said troughs certain of the rivets will travel along the narrowed lower ends of the troughs, with their shanks within the lower ends of the troughs and their heads exterior to the same. If the rivets should not be fed in this manner, the upper ends of the chutes are so formed that they will force the said rivets out of the way, so 45 as to insure the proper feeding of all the rivets which remain down the chutes. The overflow-reservoir K will receive the surplus rivets which are not engaged by the lower ends of the said troughs. As the rivets slide along 50 down the lower ends of the troughs J J' their heads are caused to enter the interiors of the chutes L L', while their shanks or stems project rearwardly therefrom through the open slots in the backs of the said chutes. These 55 chutes L L' extend downwardly through the interior of vertically-reciprocating boxes $L^2 L^3$, the lower ends of which boxes are in close proximity to the top of the bed-plate E of the machine, where the said chutes are curved

60 toward the front, so as to present the bottom two rivets at substantially right angles to the face of the bed-plate. A vertically-reciprocating movement is imparted to the chutes L L', so as to agitate the rivets and cause 65 them to positively feed down the chutes in a manner to be hereinafter described.

A reservoir M for the eyes F is located im-

mediately to the rear of the lower ends of the chutes L L', which reservoir has an open lower end for permitting the escape of the 70 bottom eye of the stack along the bed-plate E. The eyes may be fed to the reservoir through a chute m , which leads from a point near the top of the reservoir upwardly and rearwardly to the frame H, where it may be 75 suitably supported, in the present instance by a cross-bar h^3 . This reservoir M for the eyes is formed in a supporting-block M', rising from the bed-plate E, access to the interior of the reservoir M being obtained at 80 any time by means of a removable back m' , which has a sliding engagement with the block M'. This block M' also serves to guide the rivet-chutes L L' and their attached boxes $L^2 L^3$ in their vertically-reciprocating movements, as will hereinafter more fully appear.

85 A delivery-wheel d is mounted on the shaft D in the space between the anvil C and the bed-plate E, and it is keyed to rotate with the said shaft. This delivery-wheel is provided on its periphery with a series of teeth d' and slots d^2 , extended inwardly from the face of the said teeth for receiving the eyes, with the rivets therein, from the bed-plate E and conveying the eyes and rivets, as the 90 wheel is rotated around step by step, into position to be withdrawn when brought into proximity to the anvil C, the said assembled eyes and rivets being presented to the anvil with the rivet-shanks projecting upwardly in position 95 to enter corresponding holes in the corset-steel. The eyes F are inserted into the periphery of the wheel a sufficient distance to cause the heads of the rivets to engage the face of the teeth, so that the rivets will not 100 fall out as they are being brought down to the anvil C. The delivery-wheel shaft D is further provided with a ratchet-wheel d^3 , keyed thereto, which ratchet-wheel is engaged by a pawl d^4 , carried on the free end 105 of one arm of a rocking lever N, which is hinged at n to one of the supports of the bed-plate E, in the present instance the support a^5 , the end of the other arm of the lever N being engaged by the delivery-wheel-operating cam b , fixed to the rotary shaft B. The 110 delivery-wheel is yieldingly held stationary while the pawl d^4 is returned into position to impart the next movement in a forward direction to the wheel by providing one face of 115 the delivery-wheel with an annular series of depressions d^5 , corresponding in number to the teeth on the wheel, which depressions are successively engaged by the free end of a 120 spring-arm d^6 , secured to the support a^2 of 125 the anvil C.

The hammer for riveting the eyes to the steels is denoted by O and is shown as developed into two rearwardly-extended branches $o o'$, engaged by corresponding cams $b' b^2$, 130 fixed to rotate with the shaft B. This hammer is hinged on the delivery-wheel shaft D, the front end of the hammer having secured therein the head o^2 .

The following means are employed for feeding the eyes one by one from the reservoir M, first, into position to receive the rivets, and, second, to advance the eyes, with the rivets therein, into engagement with the delivery-wheel: The bed-plate E is provided with a shallow groove e, which extends from the front of the bed-plate along its top rearwardly to the back of the same and centrally of the bed-plate. This bed-plate is further provided with a pair of deeper grooves e' e'', extended inwardly from its front to a point just to the rear of the delivery ends of the chutes L L' and in alignment with the said delivery ends of the chutes. The groove e is of sufficient width to permit the reception therein of the bottom one of the stack of eyes F. A slide P is fitted to reciprocate on the bed-plate E—in the present instance by dovetailing the top of the bed-plate into the bottom of the slide. This slide F is provided with an eye-feeding tongue p, fitted to reciprocate in the groove e. The slide is positively forced forward by means of a cam b³, fixed to the shaft B, and is returned to its normal rearward position by means of a retracting-spring p', one end of which is secured to the slide P and the other end to a pin a'', uprising from the base A. To prevent the jarring of the machine by the return movement of the slide under spring tension, we provide a pneumatic cushion, the cylinder p² of which is supported at the side of the bed-plate and the plunger p³ of which is secured to the slide.

The means employed for properly delivering the rivets to the eyes are arranged and constructed as follows: The block M' is provided with a front plate Q, which serves to retain the vertical reciprocating boxes L² L³ in position therein, and in the said front plate we mount a pair of vertically-reciprocating bars l l', which are held in position by upper and lower straps q q'. These bars l l' are yieldingly connected at their upper ends to the boxes L² L³, respectively, by means of collars l⁴ l⁵, which surround pins l⁶ l⁷, screwed into the tops of the said boxes. Coil-springs l⁸ l⁹ are interposed between the heads of the pins l⁶ l⁷ and the collars l⁴ l⁵, and loose leaves l¹⁰ l¹¹ embrace the pins l⁶ l⁷ and are interposed between the tops of the boxes L² L³ and the collars l⁴ l⁵. The upward movement of the boxes, and thereby the chutes, is limited by means of adjusting-screws l¹² l¹³, which bear against the heads of the pins l⁶ l⁷. The boxes are held normally at the limit of their downward movement by means of retraction-springs l¹⁴ l¹⁵, having their upper ends engaged with the collars l⁴ l⁵ and their lower ends engaged with the front plate Q of the block M'. Adjusting-screws l¹⁶ l¹⁷ pass through the collars l⁴ l⁵ and are arranged to accurately adjust the limits of the downward movements of the bars l l'. The lower ends of the bars l l' rest normally upon the tops of the heads of the lowermost pair of rivets. They are positively lifted away from engagement with the same after

they have been fed into their holes in the eye which has been moved into position beneath them by the following means: The bars l l' are provided with outwardly-projecting pins l¹⁴ l¹⁵, which are engaged by a rocking lever R, hinged at r to a lateral extension q² of the front plate Q, the free end of the said lever being operated by a rocking lever S, hinged at s at the side of the bed-plate E, which rocking lever is operated by a cam b⁴, fixed to rotate with the cam-shaft B. A keeper q³ serves to hold the free end of the rocking lever R in position in close proximity to the face of the front plate Q. This rocking lever R is accurately adjusted with respect to the rocking lever S by means of an adjusting-screw r', the lower end of which rests directly upon the forwardly-extended arm of the said lever S. This rocking lever R is further provided with a downwardly-extended arm r², which is arranged to engage the face of the eye F when the eye has been fed into position to receive the lowermost pair of rivets and when the lever R is at the limit of its downward movement, so as to steady the said eye, while its forward movement is temporarily arrested to receive the said pair of rivets. The next succeeding pair of rivets is temporarily prevented from dropping down into position to enter the next succeeding eye by devices carried by the bars l l'. As these devices are quite similar one only is shown—viz., the one attached to the bar l'. Near the lower end of the bar l' and projected inwardly therefrom we provide a hollow lug T, from which a pin t extends downwardly into position to engage the head of the rivet next succeeding the bottom one. This pin t has a limited sliding movement in the lug T and is held yieldingly at the limit of its downward movement by means of a spring t', located within the hollow lug and interposed between the head of the pin t and an adjusting-screw t². This pin t is so arranged that it will still engage the rivet for a short time after the bar l' has been raised to release the bottom rivet. The further upward movement of the said bar will also lift the pin t and permit the rivet held thereby to drop into position to be fed to the next succeeding eye. The lowermost pair of rivets are held yieldingly in position by means of a pair of spring-actuated sliding arms v v', mounted on the bottoms of the boxes L² L³, with their inner ends projected partially across the mouths of the chutes in the said boxes. The inner ends of the said arms v v' are beveled, as clearly shown in Fig. 13, so as to permit the lowermost pair of rivets to be positively drawn from the chutes after the rivets have been engaged with the eye.

An automatic alarm is provided for notifying the operator if from any cause the bottom eye of the stack should become cramped and not be fed by the slide P into position beneath the rivets. The alarm is operated by the following mechanism: A sliding plate U

is mounted in the block M' at the front of the reservoir M and extends from a point a slight distance above the top of the block to a point in close proximity to the top of the bed-plate 5. This plate U is supported in this position by a spring-arm u , projecting from a plate u' , fastened to and insulated from the top of the block M' . A contact-plate u^2 is secured to the top of the block M' and projects over and is spaced a slight distance above the top of the vertically-sliding plate U . Wires u^3 u^4 lead through a battery u^5 and bell u^6 , so that when the plate U is raised into engagement with the contact-plate u^2 an electrical circuit is formed, thus ringing the bell u^6 . If the bottom eye of the stack is bent or becomes cramped, it will force this vertically-sliding plate U upwardly and complete the circuit above described, thus warning the operator, who may stop the machine in any well-known manner (not shown herein) until the cause of stoppage is removed.

The operation of our invention is as follows: The rivets are fed into the rivet-reservoir 25 I and the eyes are fed into the reservoir M . After the rivets have been fed from the reservoir downwardly through the rocking troughs J J' and into the chutes L L' the practical operation of the machine is begun. The eyes are advanced one by one into position beneath the lower end of the chute, where each eye is stopped momentarily and a pair of rivets engaged therewith. The eyes are again advanced, drawing the rivets from the 30 chutes, and fed forwardly into engagement with the delivery-wheel d , which wheel brings them around step by step into proximity to the anvil C , with the shanks of the rivets projecting upwardly. The operator causes the steel to engage one of the eyes by pressing the holes in the steel over the shanks of the rivets in the eye. The eye is then withdrawn from the delivery-wheel by moving the steel a slight distance forwardly until the projection c' on the face of the anvil enters the hole in the eye, thus centering the rivets with respect to the hammer. The hammer is then depressed and completes the operation of securing the eye to the steel.

50 By the use of this machine the riveting of the eyes to the steels is materially simplified and is done in a much more rapid and efficient manner than has hitherto been possible.

It is evident that changes might be resorted to in the form, construction, and arrangement of the several parts without departing from the spirit and scope of our invention. Hence we do not wish to limit ourselves strictly to the structure herein set forth; but

60 What we claim is—

1. In combination, means for assembling eyes and rivets, a riveting device and means for conveying the assembled eyes and rivets to the riveting device, substantially as set forth.

65 2. In combination, a riveting device, a supply of eyes, a supply of rivets, means for as-

sembling the eyes and rivets and means for conveying the assembled eyes and rivets to the riveting device, substantially as set forth. 70

3. In combination, a riveting device, a reservoir for the eyes, a reservoir for the rivets, means for feeding the eyes into position to receive the rivets, means for feeding the rivets to the eyes and means for feeding the assembled eyes and rivets to the riveting device, substantially as set forth. 75

4. In combination, a riveting device, means for assembling eyes and rivets, and a delivery-wheel for conveying the assembled eyes 80 and rivets to the riveting device, substantially as set forth.

5. In combination, a riveting device, means for assembling the eyes and rivets, of a delivery-wheel, means for feeding the assembled eyes and rivets to the delivery-wheel and means for imparting a rotary movement to the delivery-wheel for conveying the assembled eyes and rivets to the riveting device, substantially as set forth. 85

6. In combination, a riveting device, an eye-reservoir a rivet-reservoir, means for feeding the eyes into position to receive the rivets, means for feeding the rivets to the eyes, a delivery-wheel for conveying the assembled 95 eyes and rivets to the riveting device and means for conveying the assembled eyes and rivets into engagement with the delivery-wheel, substantially as set forth.

7. In combination, a riveting device, means 100 for assembling eyes and rivets, a delivery-wheel for conveying the assembled eyes and rivets to the riveting device, having a plurality of teeth with inwardly-extended slots at the base of the teeth for receiving and retaining the assembled eyes and rivets until positively removed therefrom, substantially as set forth.

8. In combination, a riveting device, means for assembling eyes and rivets, a delivery-wheel, means for feeding the assembled eyes and rivets successively to the delivery-wheel and means for imparting a step-by-step rotary movement to the delivery-wheel for conveying the assembled eyes and rivets to the 115 riveting device, substantially as set forth.

9. In combination, a riveting device, means for assembling eyes and rivets, a delivery-wheel, means for feeding the assembled eyes and rivets successively to the delivery-wheel 120 and means for imparting a step-by-step rotary movement to the delivery-wheel comprising a rocking lever having a pawl-and-ratchet connection with the delivery-wheel, a main drive-shaft and a cam thereon for operating the said rocking lever at predetermined intervals, substantially as set forth. 125

10. In combination, a riveting device, means for assembling eyes and rivets, a delivery-wheel, means for feeding the assembled eyes 130 and rivets to the delivery-wheel, means for imparting a step-by-step rotary movement to the delivery-wheel for feeding the assembled eyes and rivets successively to the riveting

device and means for yieldingly stopping the delivery-wheel as each assembled eye and rivet is brought into proximity to the riveting device, comprising an annular row of depressions carried by the wheel and a spring-actuated arm in position to successively engage the said depressions, substantially as set forth.

11. In a machine for riveting eyes to corset-steels, a rotary cam-shaft, a riveting device, means for assembling eyes and rivets, a delivery device, the said means for assembling the eyes and rivets, together with the delivery device and the riveting device being under the control of the said cam-shaft, substantially as set forth.

12. In a machine for riveting eyes to corset-steels, the combination with a riveting device, comprising an anvil, a hammer, and means for successively operating the hammer, of means for feeding assembled eyes and rivets to the riveting device, substantially as set forth.

13. In a machine for riveting eyes to corset-steels, the combination with a riveting device comprising an anvil, a hammer and means for successively operating it, of means for feeding the assembled eyes and rivets into position to be engaged with the corset-steel, the said anvil being provided with a projection for centering the assembled eyes, rivets and steel with respect to the hammer and anvil, substantially as set forth.

14. In a machine for riveting eyes to corset-steels, a bed-plate, an eye-reservoir located in position to feed the eyes one by one onto the bed-plate, a rivet-reservoir arranged in position to feed the rivets in pairs into the eyes as the eyes are advanced along the bed-plate, means for advancing the eyes along the bed-plate for receiving the rivets, a riveting device and means for conveying the assembled eyes and rivets to the riveting device, substantially as set forth.

15. In a machine for riveting eyes to corset-steels, a bed-plate, an eye-reservoir arranged to feed the eyes one by one onto the bed-plate, a rivet-reservoir for feeding the rivets in pairs to the eyes, means for advancing the eyes one by one along the bed-plate into position to receive the rivets and means for releasing the bottom pair of rivets when an eye is brought into position beneath the same, substantially as set forth.

16. In a machine for riveting eyes to corset-steels, a riveting device, a bed-plate, an eye-reservoir for feeding the eyes one by one onto the bed-plate, means for advancing the eyes along the bed-plate, a rivet-reservoir, means for alining rivets and for feeding them in pairs successively to the eyes when the eyes are advanced into position, and means for feeding the assembled eyes and rivets to the riveting device, substantially as set forth.

17. In a machine, for riveting eyes to corset-steels, a bed-plate, an eye-reservoir arranged to feed the eyes one by one onto the bed-plate,

means for advancing the eyes along the bed-plate, a rivet-reservoir, a pair of chutes for receiving the rivets and feeding them in pairs into close proximity to the bed-plate and means for releasing the bottom pair of rivets when an eye has been fed beneath the same, substantially as set forth.

18. In a machine for riveting eyes to corset-steels, a bed-plate, an eye-reservoir arranged to feed eyes one by one onto the bed-plate, means for advancing the eyes along the bed-plate, a rivet-reservoir, a pair of chutes arranged to receive the rivets and feed them in pairs into close proximity to the bed-plate, means for releasing the bottom pair of rivets when an eye has been brought into position to receive them and means for temporarily holding the next succeeding pair of rivets, substantially as set forth.

19. In a machine for riveting eyes to corset-steels, a bed-plate, an eye-reservoir arranged to feed the eyes one by one onto the bed-plate, means for advancing the eyes along the bed-plate, a rivet-reservoir, chutes arranged to receive the rivets and feed them in pairs into close proximity to the bed-plate and means for reciprocating the chutes vertically for insuring the proper feeding of the rivets, substantially as set forth.

20. In a machine for riveting eyes to corset-steels, a rocking trough arranged to receive the rivets therefrom and aline them, a chute arranged to receive the alined rivets from the trough and deliver them at a predetermined point and means for imparting a vertical movement to the chute and thereby oscillate the rocking trough for properly feeding the rivets, substantially as set forth.

21. In a machine for riveting eyes to corset-steels, a bed-plate, an eye-reservoir arranged to deliver the eyes one by one onto the bed-plate, a slide arranged to reciprocate on the bed-plate, a rotary shaft having a cam thereon for positively moving the slide in a forward direction, a spring for returning the slide to its normal position and a pneumatic cushion for cushioning the backward movement of the slide, substantially as set forth.

22. In a machine for riveting eyes to corset-steels, a bed-plate having a shallow eye-receiving groove and a pair of rivet-receiving grooves therein, an eye-reservoir arranged to deliver the eyes one by one into the eye-receiving groove, a slide having a tongue arranged to travel along in the said groove for advancing the eyes and means for feeding the rivets to the eyes when the eyes are over the rivet-receiving grooves, substantially as set forth.

23. In a machine for riveting eyes to corset-steels, a bed-plate, an eye-reservoir arranged to feed the eyes one by one onto the bed-plate, a slide arranged in a normal position a distance above the bed-plate sufficient to permit the bottom eye in the reservoir to be slid freely beneath the same and an electric signal arranged to be operated by the closing of

a circuit by the upward movement of the slide caused by an uneven eye or the cramping of the eye when it is advanced along the bed-plate and means for advancing the eye 5 along the bed-plate, substantially as set forth.

24. In combination, a bed-plate, a block mounted thereon, a rivet-chute, a vertically-reciprocating box connected therewith and mounted in the said block and means for reciprocating the said box, substantially as set forth.

25. In a machine for riveting eyes to corset steels, a bed-plate, a block mounted thereon, a pair of vertically-sliding boxes mounted in the block, a pair of rivet-chutes connected with the boxes arranged to feed pairs of rivets into proximity to the bed-plate at substantially right angles thereto, a pair of vertically-sliding bars mounted in the block and 20 connected with the said boxes, the lower ends of the said bars resting upon the heads of the lowermost pair of rivets and means for reciprocating the said bars and thereby the boxes vertically, substantially as set forth.

26. In a machine for riveting eyes to corset steels, a bed-plate, means for feeding eyes one by one along the same, means for feeding pairs of rivets into position to enter holes in the said eyes, a rocking lever having an arm 30 arranged to rest upon the eye as the rivets

are fed thereto and means for raising and lowering the said arm, substantially as set forth.

27. In a machine for riveting eyes to corset steels, a bed-plate, a block mounted on the same, a vertically-sliding box mounted in the said block, a rivet-chute for feeding rivets to the box and delivering them therefrom, means for reciprocating the said box and rivet-chute and means for adjusting the limit of the upward movement of the said box, substantially as set forth.

28. In a machine for riveting eyes to corset steels, a bed-plate, a block thereon, a vertically-reciprocating rivet-feeding box mounted in the said block, a vertically-reciprocating bar connected to said box and sliding in said block and means for adjusting the limit of the downward movement of the said bar, substantially as set forth.

In testimony that we claim the foregoing as our invention we have signed our names, in presence of two witnesses, this 10th day of September, 1900.
